IGNITER AND LAMP PLUG

Alfred J. Kroll, Forestville, and Arthur W. Schnick, Meriden, Conn., assignors to The Cuno Engineering Corporation, Meriden, Conn., a corporation of Connecticut

Application February 20, 1948, Serial No. 9,756

7 Claims. (Cl. 171—97)

1

My invention relates to lighters especially intended for use on motor vehicles for lighting cigars, cigarettes and pipes and also serving for illumination.

It is intended particularly for use in sockets such as shown and described in application Serial Number 686,188, filed July 26, 1946. The plug in such a device has an igniter element and is removably mounted in a stationary socket which has an outer grounded circuit terminal and an inner circuit terminal and the plug when inserted may be held normally stationary in an open circuit position or pushed further in to close a circuit and energize the igniter coil. Such plugs may be automatically latched in closed circuit position and automatically released when ready for use or held manually in closed circuit position and removed when desired for use.

My present invention relates to plugs of this character which are also provided with electric light bulbs suitable for reading in a car.

The main object is to provide a simple, compact form of construction which can be used in an ordinary socket interchangeably with plugs of the usual non-illuminating type.

An important object is to make the plug principally of metal and eliminate the use of molded insulation in the plug body.

I accordingly provide a plug having two relatively rotatable parts, one part having an igniter element at its outer end and the other part having a rotatable lamp bulb and knob at the other end. These two parts are provided with internal switch contacts connected respectively between the igniter element and a socket terminal and between a terminal of the lamp bulb and an igniter terminal so that when the plug is inserted in a socket in closed circuit position, the igniter coil and lamp filament are either in series or the lamp filament is short circuited depending upon the relative rotation of the knob and bulb with respect to the igniter element.

In the first case, the lamp will be lighted because of the difference in resistance between the igniter coil and filament and in the second case the igniter only will be energized.

Fig. 1 is a longitudinal side and sectional view of one form of plug involving the invention with the parts in position for ignition.

Fig. 2 is a cross sectional view showing the switch contacts in the position of Fig. 1.

Fig. 3 is a view similar to Fig. 1 but with the parts in position for using the lamp.

Fig. 4 is a cross sectional view showing the switch contacts in the position of Fig. 3.

2

Fig. 5 is a cross sectional view taken on the plane of the line 5—5 in Fig. 3.

Fig. 6 is a side view and section of the outer sleeve.

Fig. 7 is a face view of the insulating abutment washer for the sleeve of Fig. 6.

Fig. 8 is a side view and section of one of the switch contacts.

Fig. 9 is an end view of the contact of Fig. 8.

Fig. 10 is a side view and longitudinal section of the lamp socket and its switch contact extension.

Fig. 11 is an end view of the same.

Fig. 12 is a side view and section of the center contact.

Fig. 13 is an end view of the contact of Fig. 12.

Fig. 14 is a face view of one of the centering washers.

Fig. 15 is a face view of another centering washer.

Fig. 16 is a face view of a bushing.

Fig. 17 is a diagram of the circuit connections with the lamp in series with the igniter coil.

In the form shown, the plug has a conventional igniter element having a resistance coil 10 enclosed in a circuit terminal cup 11 and having a central stud 12 insulated from the cup. The flange or rim of the cup is adapted to engage the "hot" contact of a supporting socket when the plug is inserted sufficiently. This may be a thermostatic latch or a simple contact.

The main outer metallic sleeve 13 has a peripheral circuit terminal 14 adapted to engage the inner wall of the socket (not shown) when the plug is inserted sufficiently. This sleeve is insulated by a washer 15 from the igniter cup. The switch contact 16 is of cup-like form of elongated cross section and mechanically and electrically connected to the center stud 12 of the igniter element but electrically insulated from sleeve 13.

The outer ring 17 fits in the usual socket and has an outer flange 18 serving as a stop and an inner curled flange 19. The insulating abutment washer 20 is secured on the lugs 21 at the end of sleeve 13. The spring 22 is compressed between flange 19 and washer 20 for retracting the plug. Ring 17 has a number of lugs 17' (see Figs. 1 and 3) serving to space the principal part of the ring from the flange 14.

The lamp bulb 23 is of the usual type having an outer sleeve terminal 24 and a center terminal 25. A tubular member 26 (see Figs. 10 and 11) serves at one end as a socket for the lamp bulb and is surrounded by a bushing 27 onto which the knob

23 is screwed. The other end 29 of this member serves as an outer switch contact and is indented at 29' so as to engage switch contact 16 when the lamp is to be cut out.

The center switch contact 30 is of cup-like form but of elongated cross-section (see Figs. 12 and 13). This has a flange 31 and is positioned in the insulating washers 32 and 33 so that they will rotate together. One washer 33 is shaped with respect to the inside of the tubular member 29, and the other washer 32 is shaped to fit into tubular member 29, but shaped to allow clearance for two ears 13' bent in on member 13.

These washers 32 and 33 fit upon and support the inner contact cup 30 and tie the rotating movements of the inner contact cup 30 and tubular member 29 together, so that when the tubular member 29 is rotated 90° the inner contact cup will also be rotated 90°. The two ears 13' on member 13 fit into the slots 29' in member 29 which limits the angle of rotation. Spring 34 connects contact 30 to the lamp contact 25.

When the parts are in the position shown in Figs. 1 and 2 and the plug is inserted in a socket, the circuit will be from cup 11, coil 19, stud 12, switch contact 16, tubular switch contact member 29, socket 26, ring 27, sleeve 13 to ground terminal rim 14 thus heating the resistance coil.

By rotating the knob and attached parts with respect to the igniter and attached parts contact 29 will be disconnected from contact 16 so that they are related as in Figs. 3 and 4, the igniter and lamp will be in series and the lamp will be lighted, the circuit being from cup 11 to coil 19, stud 12, switch contact 16, contact 30, spring 34, lamp contact 25, filament of 23, base contact sleeve 24, socket 26, ring 27, sleeve 13 and ground terminal 14.

The parts are so constructed and arranged that when the lamp has been ignited the plug may be readily turned so as to direct the beam of light in various directions. When the plug is released, the spring 22 will retract the igniter element so as to break the circuit in the usual way.

If the plug is held by thermostatic latches they will release the plug when they get hot enough to retract them from the igniter cup.

In case the switch parts were left with the lamp and igniter in the series position, the lamp will light up when the plug is again pushed into the socket and the operator will thus be notified that he must rotate the knob if he wishes to use the igniter.

Fig. 17 is a diagram of the circuit when the plug is in a socket having terminals 36 and 37 engaged by the plug terminals 11 and 14, respectively, and the plug is in position so that the igniter coil 19 is in series with the lamp filament 23. By rotating the plug counterclockwise with its switch contacts 29 and 30, the contact 30 of the knob part is disconnected from contact 16 of the igniter element so as to cut out the lamp, and the switch contact 29, which is always in contact with the sleeve contact 13, engages contact 16 thus reclosing the circuit through the igniter coil 19 and putting the plug in condition for use as an igniter.

We claim:

1. A combined igniter and lamp plug for use in a supporting socket and having a front portion with an igniter element on one end and a rear portion with a knob and lamp on the opposite end, said rear portion being rotatable through approximately 90° with respect to the front portion, said front portion having contact terminals for engaging terminals in the supporting socket and

switching means contained in the plug comprising switch contacts carried by the front portion and coacting switch contacts carried by the rear portion for short circuiting said lamp when the knob and lamp portion is turned in the socket with respect to the igniter element portion.

2. A lighter plug for use in a socket having an outer terminal contact sleeve and a central terminal contact comprising an igniter element having a coil with a contact at its outer end for engaging the central terminal contact of such a socket, a first switch contact connected to the inner end of the igniter coil, a knob rotatable with respect to said igniter element containing a lamp bulb having two terminals, one of which lamp terminals has a switch contact to be connected to said first switch contact, an outer contact terminal adapted to engage the outer terminal contact sleeve when the plug is inserted into one position in said socket and a second switch contact connected to the other lamp terminal and to said outer central terminal and rotatable with the knob.

3. A combined igniter and lamp plug for use in an electric socket having outer and inner contacts, an outer cylindrical metal sleeve having a peripheral circuit terminal contact, an igniter element mounted on one end of said sleeve, but insulated therefrom, said element having a resistance coil with an outer circuit terminal contact and a central terminal, a switch member connected to said central terminal and extending within said outer sleeve, a contact sleeve rotatable in said outer sleeve and having a lamp socket on one end, a central lamp terminal supported by said contact sleeve within said switch member and constituting a switch contact and a hollow knob secured to said contact sleeve for enclosing a lamp bulb, said central lamp terminal and said contact sleeve being rotatable with respect to said outer sleeve and the attached parts.

4. A combined igniter and lamp plug for use in an electric socket having outer and inner contacts, an outer cylindrical metal sleeve having a peripheral circuit terminal contact, an igniter element mounted on one end of said sleeve but insulated therefrom, said element having a resistance coil with an outer circuit terminal contact and a central terminal, a cup-like switch member of elongated cross-section connected to said central terminal and extending parallel with said outer sleeve, a contact sleeve rotatable in said outer sleeve and having a lamp socket on one end, a cup-like lamp terminal supported within said switch member and constituting a switch contact and a hollow knob secured to said contact sleeve for enclosing a lamp bulb, said knob, said lamp terminal and said contact sleeve being rotatable with respect to said outer sleeve and the attached parts.

5. A combined igniter and lamp plug comprising an igniter coil having a circuit terminal at one end for engagement with a live contact in a socket and a switch contact connected to the other end of the coil, an outer terminal shell mechanically fixed to the circuit terminal but insulated therefrom, a rotatable tubular member having a lamp socket and a lamp at its outer end and a switch contact at its inner end within said terminal shell and adapted to be rotated into and out of engagement with the switch contact that is connected to the igniter coil, a central switch contact carried by and rotatable with said tubular member and connected to a lamp contact and a knob partially enclosing said lamp and constituting means for rotating said tubular

member and the switch contacts carried thereby.

6. A combined igniter and lamp plug formed of two relatively rotatable parts, the first part comprising an igniter element with a contact at one end for engaging a live terminal of a socket and a central stud, a switch member electrically connected to said stud and an outer carrier sleeve surrounding said switch member and having a peripheral contact for engaging a ground terminal in a socket, said carrier sleeve being insulated from said igniter element, the other part of the plug comprising a metallic tubular member rotatable in said outer carrier sleeve and in electrical connection with said sleeve, one end of said tubular member constituting a lamp socket and the other end constituting a switch member engageable with the switch member of the first part of the plug, a central switch contact centered in said tubular member and rotatable therewith and engageable with the switch member of the first part, a center contact connected to said central switch contact for engagement with the center contact of a lamp held in said socket and a knob connected to said tubular member for rotating said second part with respect to the first part.

7. A combination igniter and lamp plug comprising an igniter unit having a central stud, two tubular extensions secured to said stud, one in-

side the other, the inner extension constituting a switch member electrically connected to said igniter stud and the outer extension having a sleeve portion with a contact rim adjacent the igniter unit for grounding in a supporting socket, a tubular member having a switch contact portion at one end rotatable about said switch member within said sleeve portion, the other end of said tubular member constituting a lamp socket, a lamp bulb in said socket having a center contact connected to the first-mentioned switch member, a knob secured to said tubular member and housing said lamp bulb and an outer spring-pressed ring slidably mounted on said outer sleeve for mounting in a supporting socket.
